UNITED STATES PATENT OFFICE.

EMERY L. BULKLEY, OF PAINTED POST, NEW YORK, ASSIGNOR TO INGERSOLL-RAND COMPANY, OF JERSEY CITY, NEW JERSEY, A CORPORATION OF NEW JERSEY.

REGULATOR FOR FLUID-COMPRESSORS.

1,211,074.

Specification of Letters Patent. Patented Jan. 2, 1917.

Application filed December 5, 1914. Serial No. 875,589.

To all whom it may concern:

Be it known that I, EMERY L. BULKLEY, a citizen of the United States, residing at Painted Post, in the county of Steuben and 5 State of New York, have invented a certain new and useful Improvement in Regulators for Fluid-Compressors, (Case A,) of which the following is a specification.

This invention relates to regulators for 10 fluid compressors, and more particularly to regulators wherein to reduce the load on the compressor the intake of the compressor is closed and the discharge line opened to atmosphere whenever the pressure in the receiver reaches a predetermined amount. It has been proposed in this type of regulating mechanism to operate both the intake closing valve and the discharge line opening valve simultaneously, by admitting compressed fluid from a pressure controlled 15 valve to the operating motors of both intake and discharge line valves at the same time. In cases, however, where the compressor is unloaded at frequent intervals, there is a considerable waste of energy, in 20 that all the air in the compressor at the time the unloading valves are operated is pumped through the compressor and out into the atmosphere.

25 The object of the present invention is to provide means whereby the discharge line unloading valve will not be opened to atmosphere until a short time after the intake valve is closed. This will allow all, or a large portion, of the air in the compressor 30 to pass through the discharge line and to the receiver before the discharge line valve is opened. With this object in view, a regulating mechanism has been devised, a practical embodiment of which is represented in 35 the accompanying drawing, which shows an elevation of a compressor with the important parts of the regulating mechanism in section.

40 The compressor, as shown, comprises a low pressure cylinder 1 and a high pressure cylinder 2 connected by an intercooler 3. In the inlet pipe 4 which leads into the low pressure cylinder is an intake closing valve 5 which closes against a seat 6. The valve 5 is opened or closed by a piston 7 which slides in a cylinder 8. In the discharge line 9 of the compressor which leads 45 to a receiver 10 is placed a discharge line unloading valve 11 which controls a port 12

leading by a pipe 13 to atmosphere. In the discharge line 9 is also a check valve 14 which prevents the return of fluid from the receiver 10 when the port 12 is open. The discharge line unloading valve 11 and check valve 14 may be of any well known construction, but are here shown as disclosed in the patent to William F. Treiber, No. 1,093,299 dated April 14th, 1914. These valves 11 and 14 are supplied with operating fluid through a pipe 15 of considerable length which opens into the side of cylinder 8 at a point just uncovered by the piston 7 when the valve 5 is closed. Fluid is admitted to the cylinder 8 at a predetermined receiver pressure through a pipe 16 by a pressure controlled valve mechanism 17, such as shown, for instance, in the application of Castle and Rogers, Serial No. 791,709 filed September 25th, 1913, this valve 17 being connected with the receiver 10 by a pipe 18, this connection not being shown.

50 In operation, when the pressure in the receiver 10 reaches a predetermined maximum, the valve 17 operates to admit fluid through the pipe 16 to cylinder 8. This will move the valve 5 upwardly, closing off the intake of the compressor. After the valve 5 closes, pipe 15 will be open to the pressure in the cylinder 8, but, due to the length of the pipe 15, the discharge line valve 11 will not open immediately, but will be retarded for perhaps several strokes of the compressor, allowing practically all of the air in the compressor to be passed by check valve 14 55 into the receiver before this valve 11 opens. In this way very little air which has been already compressed and has hence consumed energy, will be lost. In my co-pending application, Serial Number 875,589, filed December 5th, 1914, I have claimed broadly the combination of a compressor, its receiver, a fluid operated discharge line unloading valve mechanism, a fluid operated intake closing valve, means for admitting fluid to operate said valves at a predetermined receiver pressure and means for delaying the action of said fluid in operating said discharge line unloading valve mechanism, and the claims in the present application are directed to a specific modification of the broad idea embodied in the above mentioned application.

55 It is to be understood that while the present showing and description discloses only

one specified modification of the invention, other forms and modifications are included in the spirit and scope of the same as expressed in the claims.

5 5. What I claim is:

- 10 1. In a regulator for fluid compressors, in combination, a compressor, its receiver, a discharge line unloading valve mechanism, an intake closing valve, a valve mechanism for operating said intake valve at a predetermined receiver pressure and means controlled by the movement of said intake valve to operate said discharge line valve after said intake valve has operated.
- 15 2. In a regulator for fluid compressors, in combination, a compressor, its receiver, a discharge line unloading valve mechanism, an intake closing valve, valve mechanism for closing said intake valve at a predetermined receiver pressure, and a conduit for con-
- 20

veying fluid to operate said discharge line valve controlled by the movement of said intake closing valve, to open said discharge valve after said intake valve has closed.

- 25 3. In a regulator for fluid compressors, in combination, a compressor, its receiver, a discharge line opening valve, an intake closing valve, valve mechanism for closing said intake valve at a predetermined receiver pressure, a piston for operating said intake closing valve, and a fluid conduit leading to said discharge valve opened to a fluid supply by the movement of said piston in closing said intake valve.

In testimony whereof, I have hereunto set 35 my hand.

EMERY L. BULKLEY.
